UNITED STATES PATENT OFFICE.

WOLFGANG E. SCHWARZMANN, OF LONGMEADOW, MASSACHUSETTS, ASSIGNOR TO AMERICAN BOSCH MAGNETO CORPORATION, OF SPRINGFIELD, MASSACHUSETTS, A CORPORATION OF NEW YORK.

SPARK-ADJUSTING APPARATUS.

Application filed December 23, 1920. Serial No. 432,707.

To all whom it may concern:

Be it known that I, WOLFGANG E. SCHWARZMANN, a citizen of the United States, residing at Longmeadow, in the county of Hampden, State of Massachusetts, have invented certain new and useful Improvements in Spark-Adjusting Apparatus; and I do hereby declare the following to be a full, clear, and exact description of 10 the invention, such as will enable others skilled in the art to which it appertains to make and use the same.

The present invention relates to a short-circuiting device for timing mechanism, such 15 as is used in magneto ignition systems, and particularly magnetos having an interrupter housing carrying an end cap and a timing arm.

In devices for short-circuiting the timing 20 mechanisms of magnetos, it was usual heretofore to make special provisions for insulating the end cap from the interrupter housing and insulating the post, upon which was pivotally mounted the spring clip that 25 maintains the end cap in place upon the housing, from the magneto frame or casing, a resilient electrical conductor being usually 30 electrically connected to the end cap and the interrupter fastening screw within the housing, and for the housing to carry an external projection, which when the housing is 35 rotated into fully retarded position, would contact with the post and thus shunt the primary circuit from the interrupter 40 through the end cap and the post to ground by way of the housing, thus making an indirect way of grounding or short-circuiting the interrupter and requiring the insulating of the end cap from the housing and the post from its mounting on the magneto frame or casing.

It is, therefore, an object of my invention to construct a magneto with a primary circuit shunting device which omits the insulating means for the end cap as well as for the post upon which the spring clip is mounted, and also to enclose or house the short-circuiting device within the interrupter housing so that the relatively movable 45 circuit closing means may be protected from contact by outside objects.

In accordance with one part of the invention a magneto having a mechanical interrupter and an interrupter housing comprising

ing a movable cam ring and an end cap, has 55 means, such as an anchoring member, preferably in the form of a forked member, for holding the end cap stationary, such means being preferably connected to the end cap and a post located on the magneto adjacent 60 the cam ring, as by fastening the anchoring member to the end cap and in engagement with the post or by fastening an end of the forked member to the cap and by spanning the post at the other end thereof, together 65 with short-circuiting contacts, preferably enclosed within the interrupter housing, and comprising an insulated contact carried by the end cap and electrically connected to the interrupter, and a grounded contact carried 70 by the cam ring and engageable with the insulated contact at the fully retarded timing position of the cam ring so as to short-circuit the primary circuit of the magneto. The enclosing of the contacts inside the 75 housing protects them from injury and from premature short-circuiting by contact therewith by outside objects.

In the accompanying drawing, illustrating preferred and modified embodiments of 80 the invention:

Fig. 1 is an end view of a magneto with a short circuiting device mounted in position upon the mechanical interrupter thereof; Fig. 2 is a part side view and a part sectional view taken on line 2—2 of Fig. 1; Fig. 3 is a transverse sectional view taken on line 3—3 of Fig. 2; Figs. 4 and 5 are views similar to Figs. 2 and 1, respectively, showing another embodiment of the invention; Fig. 6 is a view similar to Figs. 2 and 4 showing a still further embodiment of the invention; Fig. 7 is a sectional view of the end cap used in the embodiment shown in Fig. 6; Figs. 8 and 9 are views similar to Figs. 6 and 7, 90 respectively, showing a still further embodiment of the invention.

Referring more particularly to the drawing, a magneto 1 has an interrupter housing 2 at an end thereof, a timing lever 3 being 100 connected to a cam ring 4 rotatably supported upon the housing in a well known manner. Within the interrupter housing may be included the usual interrupter elements comprising an interrupter fastening screw 105 5 with which engages a contact brush 6 carried by a resilient conducting strip 7 mounted upon an end cap 8 held in bearing or

thrust contact with the end of the cam ring 4 by a spring 9 pivotally mounted upon the end of a post 10 located on the magneto adjacent the cam ring 4. The strip 7 is fastened to the end cap 9 by a screw 11 which is screwed into an insert molded into the base 12 of insulating material on the cap 9, an insulating strip or washer 13 being interposed between the end of the strip 7 and the inner surface of the cap 9 in order that current from the interrupter to the strip 7 will not be short-circuited through the cap 8 as will more clearly appear hereinafter. The outer end of the insert may be threaded to receive a binding nut 14. Between the end of the strip 7 and the head of the screw 11 is connected an angular contact member 15 with one of its legs 16 extending parallel to the axis of the interrupter and cam ring and curved or arc-shaped to enable its ready engagement with a screw contact 17 fastened to the cam ring 4, the screw being grounded through the casing of the magneto through the cam ring 4 and the housing 2.

In the form or embodiment illustrated in Figs. 1, 2 and 3, the spring 9 has a projection 18 at its inner end pressing into a depression 19 for holding the end cap 9 against the end of the cam ring 4, the other end of the spring 8 being pivotally secured to the end of the post 10, so that the spring when grasped by a clip 20 and turned about the axis of the post 10 for disengagement and engagement of the spring 9 with the end cap. For the purpose of maintaining the end cap 8 and the parts, such as the contact brush 6, spring 7 and contact member 16, in stationary position during the retarding movement of the cam ring 4 and the contact screw 17, the cap 8 has fastened thereto, by means of rivets 21, an end of an anchor member 22, the other end of this member being forked or having prongs 23 spanning the post 10 so that any tendency to rotate the end cap 8, due to its frictional engagement with the angularly moving cam ring, will be prevented since angular movement of the anchor member about the axis of the interrupter and cam ring is prevented by reason of the contact of the prongs 23 on both sides of the post. In this way the end cap 8 and the contact part 16 are held stationary and the contact screw 17 is moved into or out of contact with the part 16 as the cam ring 4, carrying such screw 17, is angularly moved respectively, to or from fully retarded position. Upon the engagement of the contact parts 16 and 17, the primary circuit normally passing through the interrupter elements is short-circuited or shunted to ground through the end fastening screw 5, contact brush 6, spring strip 7, angle member 15, contact leg 16, contact screw 17 and cam ring 4 to the housing 2 and

hence to ground. In Fig. 3 is illustrated, in full lines, the position of the timing lever 3 during the normal operation of the magneto, at which time the contact screw 17 is separated from the contact part 16, and in dotted lines is shown the position occupied by the timing lever 3 and contact screw 17 when the lever and cam ring 4 are rotated to fully retarded position at which time the contact screw 17 is in contact with the contact part 16 and the interrupter primary circuit is shunted to ground.

In the embodiment illustrated in Figs. 4 and 5, the end cap 8^a is held from rotation by means of a pair of rivet pins 24 rigidly fastened to the cap 8 and located one on each side of and in contact with the side edges of the spring 9, so that any tendency to rotate the cap 8^a during the angular movement of the cam ring is prevented since angular movement of the pins 24, about the axis of the cam ring 4, cannot occur due to the contact of the pins 24 at both edges of the spring 9.

In the form of device shown in Figs. 6 and 7, the end cap 8^b has a radially extending depression or trough 25 having side shoulders 26 and within which the spring 9 is adapted to be seated with its side edges in contact with the shoulders 26, so that tendency to rotation of the cap 8^b is prevented by the engagement of the shoulders 26 with the lateral edges of the spring 9.

In the structure shown in Figs. 8 and 9, the end cap 8^c is made of insulating material, such as a condensation product, as bakelite, and has a substantially flat radial recess 27 having lateral shoulders 28 and within which the spring 9 is adapted to rest with the side edges of the spring engaged by the shoulders 28, so that tendency to rotation by the cap 8^c is prevented by the contact of the shoulders 28 with both sides of the spring 9. The cap 8^c also has a boss 12^c in which is embedded, when the cap is molded, an insert 29 having an annular groove 30 for maintaining it in place in the insulating material and being suitably threaded to receive the threaded portion of the screw 11 for securing the contact member 15 and the spring strip 7 in place. It will be observed here that inasmuch as the cap 8^c is of insulating material the insulating washer 13 of the forms of devices shown in Figs. 1 to 7 inclusive, is omitted. It will also be noted that, inasmuch as no lead need be connected to the usual binding post or nut 14, the latter can be omitted as shown in Figs. 8 and 9, such binding member 14 being shown in Figs. 1 to 7 inclusive, merely to indicate that the invention is applicable to or adapted for use with present end caps.

The primary circuit of the magneto passes through the cam shaft, which carries the fastening screw 5, to the contact carrying 130

elements of the interrupter mechanism in the usual manner, but at certain times of operation it may be desirable for the primary circuit of the interrupter to be short-circuited or grounded so that no induced current may be effected in the secondary circuit of the ignition system, particularly in the event of driving an automobile down hill when it is desired to use the engine as a 10 brake, either with or without the mechanical brakes usually provided on the vehicle. In such case, as in others, it is usual to retard the ignition to the full extend and to provide some means of short-circuiting or grounding 15 the primary circuit at the fully retarded position of the ignition device. Heretofore, the grounding or short-circuiting shunt passed from the fastening screw through a conducting piece electrically connected to the end 20 cap of the interrupter housing, and thence through an end cap spring and the post supporting the spring. It is necessary in such cases to insulate both the cap from the housing and the post from the magneto casing, 25 and for the interrupter housing to carry a contact which, when the housing is rotated to fully retard position, would engage with the post for completing the grounding shunt by way of the interrupter housing. It will be 30 apparent from the above description and illustration upon the accompanying drawing, that I have eliminated the necessity of insulating the end cap and the post from the interrupter housing and the magneto casing, 35 respectively, and by otherwise simplifying the structure in many respects.

Having thus disclosed my invention what I claim is:

1. A magneto having a mechanical interrupter and an interrupter housing comprising a movable cam ring and an end cap, means for holding said cap stationary, an insulated contact carried by said cap and electrically connected to said interrupter, 45 and a grounded contact carried by said cam ring and engageable with said insulated contact at the fully retarded timing position of said cam ring for short-circuiting said magneto.
- 50 2. A magneto having a mechanical interrupter and an interrupter housing comprising a movable cam ring and an end cap, and

a post on said magneto located adjacent said cam ring, means connected to said post and said cap for holding said cap stationary, an 55 insulated contact carried by said cap and electrically connected to said interrupter, and a grounded contact carried by said cam ring and engageable with said insulated contact at the fully retarded timing position of 60 said cam ring for short-circuiting said magneto.

3. A magneto having a mechanical interrupter and an interrupter housing comprising a movable cam ring and an end cap, and 65 a post on said magneto located adjacent said cam ring, an anchoring member fastened to said cap and engaging said post for holding said cap stationary, an insulated contact carried by said cap and electrically connected to 70 said interrupter, and a grounded contact carried by said cam ring and engageable with said insulated contact at the fully retarded timing position of 75 said cam ring for short-circuiting said magneto.

4. A magneto having a mechanical interrupter and an interrupter housing comprising a movable cam ring and an end cap, and a post on said magneto located adjacent said cam ring, a forked member fastened at one 80 end to said cap and the other end thereof spanning said post for holding said cap stationary, an insulated contact carried by said cap and electrically connected to said interrupter, and a grounded contact carried by 85 said cam ring and engageable with said insulated contact at the fully retarded timing position of said cam ring for short-circuiting said magneto.

5. A magneto having a mechanical interrupter and an interrupter housing comprising a movable cam ring and an end cap, means for holding said cap stationary, an 90 insulated contact carried by said cap and electrically connected to said interrupter, 95 and a grounded contact carried by said cam ring and engageable with said insulated contact at the fully retarded timing position of said cam ring for short-circuiting said magneto.

In testimony whereof I affix my signature.

WOLFGANG E. SCHWARZMANN.
